CLOTH WINDING MACHINE HAVING SELECTIVE SPEED CONTROL MEANS

Herman Walter Gilbert, Forest Hills, and Walter Deichmann, Mineola, N. Y.; Abner I. Gilbert and Greta V. Gilbert, executors of H. Walter Gilbert, deceased; said Deichmann assignor to Cutting Room Appliances Corp., a corporation of New York

Application May 18, 1949, Serial No. 93,896

2 Claims. (Cl. 242—75)

1

This invention relates to machines for measuring and inspecting rolls and bolts of cloth and the like.

An object of the invention is to provide a novel and improved machine for the measurement of the length of cloth in rolls or bolts, automatically, and without effort on the part of the operator.

Another object of the invention is to provide an improved cloth measuring machine which is adapted to facilitate the simultaneous inspection of the cloth being measured, during the measuring process.

A further object of the invention is to provide an improved cloth measuring and inspecting machine, which is adapted to receive any size of cloth roll or bolt, being adjustable for the size or length of any roll or bolt to be measured therein, and in which novel means are provided for quickly and easily releasing said cloth roll or bolt for demounting the same from the machine.

Another object of the invention is to provide an improved cloth measuring and inspecting machine including a selection of variable speeds controlled by means of a convenient foot pedal, to increase and decrease the speed, and also to run the machine forwardly or in reverse.

Another object of the invention is to provide eye level inspection, so that the worker can sit at the machine, if desired, for comfortable inspection of the piece goods, the controls being simple and easily reached.

Still another object of the invention is to provide a cloth measuring and inspecting machine including a front inspection board across which the cloth travels and is prevented from sagging during the inspection process, and also including an easily attachable and detachable rear inspection rack across which the cloth passes in a vertical plane for convenient inspection in this plane from the rear of the machine.

A further object of the invention is to provide an improved cloth measuring and inspecting machine which is simple in design, inexpensive to manufacture, and which is easy to operate by relatively inexperienced workers with a high degree of accuracy and speed.

Other objects and advantages of the invention will become apparent from the following description of a preferred embodiment, thereof as illustrated in the accompanying drawings, and in which:

Fig. 1 is a side elevation of the machine.

Fig. 2 is a front elevational view of the machine shown in Fig. 1, that is, as seen from the left of Fig. 1.

2

Fig. 3 is a sectional side elevational view of the machine as seen on plane 3—3 of Fig. 2.

Fig. 4 is a fragmentary plan view in detail taken on line 4—4 of Fig. 2.

Fig. 5 is a sectional elevation of the gear box and gears and shafts therein.

Fig. 6 is a sectional elevation taken on plane 6—6 of Fig. 5.

Fig. 7 is a side elevational view similar to that of Fig. 3, but showing a modified form of the invention, by means of which the machine is provided with both a front inclined inspection board and a rearward inspection rack for inspecting the cloth from the rear of the machine in a vertical plane.

Fig. 8 is a schematic wiring diagram illustrating the operation of a foot control switch for the motor;

Fig. 9 is a schematic showing of a portion of the apparatus shown in Fig. 3 and illustrating a modified or alternate use thereof; and

Fig. 10 is a top plan view of a portion of the apparatus shown in Fig. 3 and illustrating a modified form of the invention.

In the use and operation of cloth measuring and inspecting machines, it is necessary that this be quite convenient to the operator, since it is a delicate operation requiring concentration of the operator on the work at hand, namely that of measuring the length of the cloth on the roll or bolt, and also that of inspecting the cloth during the measuring operation, for defects. The machine should be readily and easily adjustable to receive any size of roll or bolt to be inspected, and should be readily adjustable as to speed and direction of rotation. The controls should be accessible, particularly the speed control, so that the operator can, from any position along the front of the machine, regulate the speed to a high degree of accuracy to facilitate the measurement and inspection of the cloth. The present invention fulfills these requirements.

In order to understand clearly the nature of the invention and the best means for carrying it out, reference will now be had to the drawings, in which like numerals denote similar parts throughout the several views.

As shown, the cloth measuring and inspecting machine has a frame with right and left end frame walls 10 and 12 respectively, made of metal or other suitable material, with integral front and rear feet 14 and 16 in each end wall and adapted to rest upon the floor 18 of the room in which the machine is placed.

Openings such as those shown at 18 and 20 may be made in the end frame walls in order to

lighten their total weight and to render the parts of the machine more visible to the operator, flanges 22 being formed integral with the walls along the edges and also surrounding each opening, to increase the strength thereof. The end frame walls are interconnected at the bottom by two lower main guide rods 24 and 26 respectively, the ends of which are inserted through matching openings in the frame walls and secured therein in any suitable manner, as by means of nuts threaded thereon. These rods 24 and 26 are preferably highly polished or lubricated to reduce friction therealong.

A lower main front roll support bracket 28 has axially aligned bearing bores formed in its lower feet ends 30 and 32 to receive slidably the guide rod 24 which thus rides thereon from left to right and vice versa along the length of the machine, the main bracket 28 also having a rearwardly inclined strut leg 34, secured at its upper end 36 to an intermediate portion of the bracket 28, and having its lower end 38 in the shape of an open rounded yoke as seen best in Fig. 3, to partially embrace the polished rod 26 so as to ride therealong, maintaining the position of the parts as shown best in Fig. 3.

At its upper end portion, the main lower bracket 28 is provided with integral upstanding studs 38 and 40, having axially aligned bores formed therein parallel to the axis of the rod 24, to receive a roll support plunger 42, which is axially slidable as seen in Fig. 2. The plunger 42 is biased toward the right as seen in that view, by the spring 44, its rightward motion being limited by the collar 46 secured on and movable with the plunger 42, and against which the spring presses. The plunger shaft extends beyond the stud 40 to the right, having mounted thereon a cone-shaped plug 48 which is adapted to enter one end of a cloth roll 50, being roughened to enhance its frictional qualities.

At the right hand end of the cloth roll 50, there is a similar cone-shaped plug 52 which enters the other end of the cloth roll, to provide support therefor, being part of a stub shaft 54 which is journaled in a suitable bearing aperture formed in the right hand end frame wall 14 of the machine. A pulley or sprocket wheel 58 is secured to the shaft 54, for rotation therewith, being driven when power is applied through a belt 62 also coupled with pulley wheel 70, which in turn is mounted on and rotatable with output shaft 72 of the gear box 74, which is also shown in Figs. 5 and 6.

It is thus apparent that through power supplied from shaft 72 of the gear box, rotation of the cloth roll 50 may be accomplished. Referring again to Fig. 2, it will be seen that the position of the main bracket 28 will depend upon the length of the cloth roll 50, and that the bracket 28 may be moved to the left or right as desired for this purpose. To hold the main bracket 28 in position, a pressure foot or brake 80 has its lower end adapted to press downwards upon the rod 24, with its upper end pivotally secured to the end 82 of a lever arm 84 by pivot pin 86, the lever arm 84 being fulcrumed in the main bracket 28 in any suitable manner and turnable about such fulcrum by means of a locking handle 88. Thus, the pressure foot or brake 80 is pressed downwards against the rod 24 by moving the handle 88 to an upright position, and released from such braking pressure, to release the bracket, by turning the handle to

either side, such as to the left as seen in Fig. 2.

To release the cloth roll 50 from the cones 48 and 52, I provide a retracting handle 90 pivotally connected to bracket 28 at 92, and connected pivotally at 94 by a pair of connecting levers 96, to the collar 46. It is apparent that turning the handle 90 counterclockwise as seen in Fig. 2 will pull the cone 48 to the left, releasing the cloth roll 50. So as not to interfere with the free rotation of the cone 48 and its shaft 42, the collar 46 may be so arranged as to engage a circular groove in the shaft 42 so as to maintain its position longitudinally of the shaft, or an integral shoulder of the shaft 42, or other well known means may be used to accomplish this result, the cones 48 and 52 being rotatable with the cloth roll 50.

Three mutually spaced parallel guide rods 100, 102, and 104 all lie in a horizontal plane above that of the lower guide rods 24 and 26 and parallel thereto, these guide rods also being secured at their ends to the frame end walls 10 and 12 by means of screws, nuts threaded on their ends, or other well known means, so as to maintain the spacing between the frame end walls and to be firmly supported thereby. An upper cloth roll support bracket 106 is slidable longitudinally along the upper guide rods 100 and 104, having a rearward extension 108 with bearing apertures formed in the hubs 112 and 114 to receive the guide rod 100, and having a bearing yoke formed at 110 to slidably engage the rod 104, the extension 108 extending beneath the guide rod 102, as seen best in Figs. 3 and 4, to clear the same.

A pressure foot 120 is pivoted in the bracket 106 at 122, with its end 124 adapted to bear in frictional engagement against the rod 100 to maintain the position of the bracket 106 on the rod 100, pressure being applied by the hand lever 126 for this purpose. A push rod or plunger 130 is slidably disposed in axially aligned openings formed in the bosses 132 and 134 of the bracket 106, having rotatably mounted on one end thereof a cone 136 adapted to engage frictionally inside one end of a cloth roll 140. A similar cone 142 is insertable inside the other end of the cloth roll 140 for frictional engagement therewith, being mounted on a shaft 144 for rotation therewith, the shaft extending out of the gear box 74.

The plunger 130 is biased toward the right as seen in Figs. 2 and 4, by means of an encircling spring 146 the right hand end of which presses against a collar 148 engaging the plunger, so that the spring pressure cannot push the plunger beyond the boss 134. A hand lever 150, which is pivoted at 152 to the boss 132, also pivotally engages at 154 one end of each of a pair of levers 158, the other ends of which engage the collar 148. Thus, by pulling the hand lever 150 toward the left, that is in a counterclockwise direction as seen in Fig. 2, the effect is to draw the cone 136 out of the cloth roll 140, so that a new roll 140 may be inserted or the old one removed. It is also apparent that by releasing the lever 126, the distance between cones 136 and 142 may be adjusted to fit any size of cloth roll 140.

A highly polished cloth guide rod or roller 160 is secured between the frame end walls 10 and 12 as shown, so that cloth may move thereover as seen best in Fig. 3, before moving across the examining board 126 which is made of wood or other suitable sheet material. The examining board has a width as long as the length

of the rod 160, being supported at its upper end edge upon the machine frame, as by engagement with a lateral tie rod 166 hung in recesses 168 formed in the frame end walls as seen in Figs. 1 and 3. The lower end edge of the examining board 162 may rest upon a similar lateral tie rod 170, shown in Fig. 3, and secured at its ends in portions 172 of the frame end walls.

After passing upwards over the guide roller 160 and over the examining board, the cloth continues upwards over the smooth upper guide roller 174 which is secured at its ends to the frame end walls, and then proceeds downwards in the direction of the arrow 176 in Fig. 3, and around another guide roller or shaft 178 which is also supported by the frame end walls and is highly polished. From roller 178 the cloth 180 proceeds rightwardly downwards as seen in Fig. 3, and around the guide rod or roller 182 which is supported at its ends by the radius arms 184, these being tensioned and biased counterclockwise by engagement with one end of spring 186 the other end of which is secured to the frame of the machine as at 188.

The cloth then moves upwards and around the surface of a counting drum 190 having a relatively larger diameter, as seen best in Fig. 3, being carried on and rotatably movable with a shaft 192 which is journaled at its ends in the frame end walls 10 and 12. A counter 194 is mounted on the machine frame adjacent the end of the shaft 192, so as to count the revolutions thereof in terms of yardage of cloth or other suitable units of measurement.

As the cloth passes over the counting drum 190, pressure is applied thereagainst by a rubber pressure roller 196 the shaft 198 of which has its ends lying in a pair of inclined slots 200 formed in the machine end walls 10 and 12, so that through force of gravity, the weight of the pressure roller causes it to exert its pressure on the counting drum and cloth passing thereover. Having passed over the counting drum in a clockwise direction as seen in Fig. 3, the cloth moves downwards over the guide rod 104, and thence over a tension roller 202, the latter being carried on its ends upon lever arms 204 pivoted about the axis of rod 104 and spring biased counterclockwise by a spring 208. The cloth 180 then passes over the cloth roll 50 in a counterclockwise direction as seen in Fig. 3, being thus wound thereon. Its yardage having been automatically counted, it has also been inspected as it passes over the inspecting board 162. In order to roll the cloth off roll 140 and onto roll 50, the shaft 54 and cone 52 have been driven by power derived from the motor 210, on shaft 212 of the gear box.

By now driving shaft 72 of the gear box instead of shaft 54, and in a suitable direction, the upper shaft 144 and cone 142 are driven, so as to reverse the direction of the cloth, winding it right back again on roll 140. Figs. 5 and 6 illustrate the construction of the interior of the gear box 74, by means of which either shaft 72 or 144 may be driven from the gear box input shaft 212.

The gear box housing 74 includes top and bottom walls 350 and 352, side walls 354 and 356, and end walls 358 and 360, mounting holes 362 and 364 being formed in the end wall 358 to receive bolts for securing the housing to the frame of the machine. The power input shaft 212 is journaled in the gear box walls 354 and 356 as seen best in Fig. 6, having a worm 366 mounted

thereon for rotation therewith. This worm 366 engages and drives a gear 368 which is mounted on and rotatable with a shaft 370 which is spaced from the shaft 212 and is disposed at right angles thereto.

The shaft 370 is journaled in the walls 358 and 360 of the gear box, preferably in anti-friction bearings 372 and 374. A stud wheel 376 is mounted on the shaft 370 for rotation therewith, having a key extending slidably into a keyway 378 formed in the surface of the shaft 370 and parallel to the axis of said shaft. In this manner, the stud wheel 376 is continuously rotatable with the shaft 370, but is yet slidably axially therealong, from left to right as seen in Fig. 5.

The stud wheel has a peripheral groove 380 which receives a crank pin 382 depending from the distal end of a crank lever 384, which is pivoted on the vertical shaft 386 and movable with the shaft 386 about its vertical axis, through a limited arc, so as to move the stud wheel 376 from left to right and vice versa. A crank handle or direction control lever 388 has its reduced end 390 extending into and secured to the upper bifurcated end of the shaft 386 for turning the said shaft for direct or reverse rotation of the machine. It is seen that the crank handle 388 extends leftwardly as seen in Fig. 6, through an opening 392 formed in a bracket 394 which is carried by the gear box and secured thereto. The upper edge of the opening 392 is recessed at several locations perpendicular to the view of Fig. 6, so that it is necessary to depress the leftward portion of the handle 388 to clear these recesses, to allow the handle to be placed in any desired recessed position, for example, center neutral, left, and right, and a spring 396 may be used to bias the handle so as to remain in any selected recess.

For driving the output shaft 144 from the input shaft 212, it is seen first that the shaft 144 is also journaled in the walls 358 and 360, and has mounted thereon for rotation therewith a gear 400. This gear 400 has its teeth intermeshing with the teeth of a gear 402 which is mounted on the shaft 370 for free rotation thereon. A stud 404 projects leftwardly from the left surface of the gear 402 as seen in Fig. 5, for engagement with one of the mating studs 406 on the stud wheel 376 when the stud wheel is moved to the right on turning the handle 388. In this manner, the stud wheel will drive the gear 402 and hence drive the shaft 144.

To drive the other output shaft 72, which is journaled in the gear box walls 358 and 360, a sprocket wheel 410 is mounted on the shaft 72 for rotation therewith. Another sprocket wheel 412 is mounted on the shaft 370 for rotation thereon, and is coupled by sprocket chain 414, with the sprocket wheel 410, so as to drive the latter. A crank stud 416 projects rightwardly from the right face of the sprocket wheel 412 as seen in Fig. 5, so that it will engage with one of the leftwardly projecting studs 418 on the stud wheel 376, when the stud wheel is moved toward the left, for driving the sprocket wheel 412. In this manner, it is seen that on moving the stud wheel to the left, the shaft 72 will be driven, instead of the shaft 144.

A brake cylinder 420 with surrounding brake band, as seen best in Figs. 1 and 5, may be mounted on one of the shafts of the gear box to regulate the speed and to stop rotation suddenly when necessary, being actuated by a brake handle 422.

The driving motor 210 is mounted on a motor base 211, which is hinged at 214 to the machine frame and wall 10, so that the weight of the motor exerts a downward pull upon the belt 216 by which its drive shaft pulley 218 is coupled to the upper driven pulley 220 mounted on the shaft 222 for rotation therewith so as to drive the shaft 222. Shaft 222 is journaled in a pair of channels or brackets 226 which are pivoted at their ends 228 as seen best in Fig. 2, to the frame end wall 10. A push rod 230 has its upper end pivotally supporting the outer end of the bracket 226, so as to be able to elevate or lower the same. At its lower end 232, the push rod 230 is pivoted to one end of a pedal lever 234 which engages the shaft 236 so as to turn the shaft about its axis, the shaft 236 being pivoted in the machine frame end walls 10 and 12 for this purpose. A treadle or step 240 is carried upon the outer ends of radius levers 244, as seen in Fig. 3, which are carried by and turn with the shaft 236, being normally biased by gravity into the positions of Figs. 1 and 3. The treadle 240 extends the entire length of the machine, so as to be easily accessible to the operator's foot at any time.

Referring now again to Figs. 1 and 2, it is seen that the gear box input shaft 212 carries a pulley 250 for rotation therewith, the pulley 250 being coupled by means of the V-belt 254 with a variable speed V-pulley 256 which is also mounted on the shaft 222 for rotation with pulley 220. The variable speed pulley 256 has two halves, one being shown on either side of the V-belt 254 in Fig. 1, and having their inner faces conical in shape. The V-belt 254 extends between these two conical pulley faces, being driven thereby, and by varying the spacing between the two faces by moving them nearer together or further apart by the push rod 230, the ratio of effective diameter of pulley 256 over that of pulley 250 is adjustable to obtain any desired speed, by merely using the foot treadle 240 for this purpose. As the spacing between the two conical faces of the V-pulley 256 is varied, the weight of the motor 210 immediately takes up any slack, since both the motor and the brackets 226 are pivoted in the frame end wall 10.

Fig. 7 shows a modified form of the invention, all the elements being the same except that it provides means for inspecting the cloth both across the examining board in an inclined plane, and also in a vertical plane along the back of the machine. To a machine of the type shown in Fig. 1, we add a pair of upright brackets 275, one at each end of the machine, and secured to the end walls 10 and 12 by means of bolts 277 and 279. The brackets 275 are interconnected by smooth guide rods or rollers 280, 282 and 284, all parallel to the shaft 192.

We provide an inspecting board 300, the upper edge of which is hung at the ends in hooks 302 formed in the brackets 275, and the lower edge of which rests upon a lateral rod 304 which is seated at its ends in the upwardly open slots 306 formed in the portions 172 of the frame end walls 10 and 12.

In the form shown in Fig. 7, it is seen that the direction taken by the cloth is somewhat different from that in Fig. 3, as follows. Being on cloth roll 140, the cloth 308 travels in the direction of the arrow 310, upwards over the left face of the inspecting board 300, and then over the upper edge of the board 300 and downwards in the direction of the arrow 312 and around the roll or rod 160. Thence it moves toward and around rod

182 and around the counting roller 190 in a clockwise direction, being counted as to yardage as already explained. Then the cloth proceeds around roll 282 and upwards in the direction of arrow 314 and over roll 280 and downwards in a vertical plane along arrow 316 in which plane it may be inspected by the operator from the rear of the machine.

Then it moves over roll 284 and downwards over tension roll 202 and onto cloth roll 50. When the inspection and measurement is completed, roll 140 is driven instead of roll 50, so as to rewind the cloth right back again on roll 140. By means of suitable changes in the shape of the members shown conical at 48, 52 and the like, to flatten them out somewhat, bolts of cloth may also be accommodated in the machine with the same ease as rolls of cloth.

While the apparatus, constructed and arranged as described above, may be used for all types and weights of material, which it is desired to measure, we have provided in accordance with our invention an alternate arrangement as illustrated schematically in Fig. 9, when the cloth to be measured is of the heavier or thick pile type. To this end there is provided an auxiliary highly polished guide rod or roller 500, similar in purpose and function to that of the rod 160, and similarly secured between the frame end walls. As noted in Fig. 9 the said rod 500 is so positioned whereby the cloth passes thereunder and thence between the roller 190 and drum 190 and over the roller 178 in substantially a straight line. There is thus provided substantially tangential contact of the cloth with the measuring drum 190 instead of the arrangement as shown in Fig. 3. A similar arrangement of one point contact with the measuring drum may also be provided in connection with the Fig. 7 form of apparatus where inspection of the cloth is desired.

While in Fig. 1 of the drawings we have shown a toggle switch 505 of usual construction for energizing the motor 210, our invention also contemplates the following foot control switch means for automatically starting the operation of the motor when the operator's foot is placed on the treadle 240, as clearly illustrated in Figs. 8 and 10.

A cable member 510 of wire or other suitable material is fixed at one of its ends to the frame 10 by a bolt member 511 or other suitable attaching means. The said cable 510 extends in a direction toward the frame 12 and is arranged parallel to and closely adjacent the treadle 240. The said cable may be disposed at about the same level as the treadle 240 in its uppermost position or slightly above the same. The opposite end of the cable 510 is attached to a switch arm 512 carrying an electrical contact portion 515. A spring 516 keeps the cable 510 relative taught and a second spring 517 stronger in action than the spring 516 normally tends to keep the switch portion 515 out of contact with the electrical contact member 520. It is thus seen from the above description that when the operator places his foot on the treadle 240, a portion of the operator's foot will rest over the cable 510. Slight pressure on the cable will cause the switch arm 512 to make electrical contact between the members 515 and 520 and thus energize the motor 210 even if the toggle switch 505 is open. Removal of the operator's foot from the treadle 240 and from the cable 510 will automatically shut off the motor 210.

The switch device parts 512, 516, 517, 515 and

520 may be housed in a suitable casing 525 fixed to the frame 12 by an angle bracket 526.

It is further noted that in accordance with our invention we have designed our apparatus in such manner that the front inspection board member 300 and rear inspection device illustrated in Fig. 7 are at average eye level so as to avoid undue eyestrain or neckstrain on the part of the operators or inspectors.

It is thus apparent that we have described a novel and improved form of machine for the measurement and inspection of cloth both on rolls and bolts, with ease and accuracy.

Although we have described our invention in specific terms, it will be understood that variations may be made in size, shape, materials and arrangement without departing from the spirit and scope of the invention as claimed.

We claim:

1. In a cloth measuring and inspecting machine comprising a frame: first means carried by said frame for supporting for rotation a first cloth roll, second means carried by said frame for supporting for rotation a second cloth roll, third means carried by said frame for supplying power to said second means to rotate the same to unwind cloth from said first cloth roll and onto said second cloth roll, the improvement comprising: said third means including a motor disposed in said frame to provide driving power, gear box means coupled to both said first means and said second means for driving the same, and including power input means in said gear box coupled to said driving motor for being driven thereby, first and second power output means in said gear box with gear shift means accessible to the operator for driving from said power input means either of said power output means as desired, and variable speed means coupling said motor and said power input means, said variable speed means comprising a first pulley mounted on and driven by said motor, a second pulley mounted on and rotatable with said power input means of said gear box, a third pulley rotatably supported on said frame and coupled to said first pulley by a belt, a variable speed pulley mounted on said frame and rotatable with said third pulley, and coupled to said second pulley by means of a belt, and means accessible to the operator for changing the speed ratio of said variable speed pulley in re-

lation to the second pulley, whereby the speed of drive of the second pulley is variable, said third pulley and said variable speed pulley being disposed on a common bracket pivoted in said frame below said second pulley, said motor pulley being disposed beneath said common bracket with said motor being pivoted off-center in said frame so that the weight of the motor acts to exert a downward bias upon said common bracket to maintain said two belts continuously under tension, said speed means accessible to the operator for changing the speed ratio including a lever pivoted in the frame and engaging said variable speed pulley for adjusting the spacing of the variable speed elements thereof to vary the speed ratio, and a treadle pivoted in said machine frame and engaging said lever for actuating said speed change lever, said treadle being substantially as long as said machine and extending lengthwise therealong for convenient accessibility to the operator at any point therealong for speed change.

2. The construction according to claim 1, characterized further in that a brake drum is carried by one of said gear box shafts, a brake band is adapted to engage said drum for regulating the speed thereof, and a control lever means is provided for actuating said brake band.
